UNITED STATES PATENT OFFICE.

MAHLON E. LAYNE AND SAMUEL N. HALL, OF LOS ANGELES, CALIFORNIA; SAID HALL
ASSIGNOR TO SAID LAYNE.

PUMP MECHANISM.

Application filed September 8, 1920, Serial No. 408,949. Renewed January 31, 1923.

To all whom it may concern:

Be it known that we, MAHLON E. LAYNE and SAMUEL N. HALL, both citizens of the United States, residing at Los Angeles, in ⁵ the county of Los Angeles and State of California, have invented certain new and useful Improvements in Pump Mechanism, of which the following is a specification.

The invention relates to pump mechanism and particularly to the means for securing a proper lubrication of the bearings for the impellers or drive shaft in the casing of a centrifugal or rotary pump. The invention has for its primary objects; the provision of an improved oiling arrangement wherein, (1) the several intermediate bearings may be independently lubricated and a proper supply of oil for each bearing insured, (2) a proper distribution of the oil ¹⁰ is secured, (3) the oil may be supplied to the pump casing intermittently and at the same time secure a continuous supply to the bearings, and (4) whereby a by-pass is provided at the intermediate pump bearing arranged to take care of any water and sand which would otherwise pass through the intermediate bearing. Certain embodiments of the invention are illustrated in the accompanying drawings wherein:—

30 Figure 1 is a partial vertical section and partial side elevation of a portion of a pump equipped with the invention; Fig. 1^a is an enlarged detail section through the bottom of one of the oil cylinders of Fig. 1; Fig. 2 is a section on the line II—II of Fig. 1; Fig. 3 is a partial vertical section showing the means of supporting the pipe line upon the shaft casing. Fig. 4 is a section on the line IV—IV of Fig. 3; Fig. 5 is a horizontal section on the line V—V of Fig. 1; and Figs. 6 and 7 are partial vertical sections and partial elevations of pumps provided with modified forms of construction.

40 Referring to Figs. 1 and 2, 1 is the outside casing member of a rotary or centrifugal pump; 2 is a portion of the inside casting member connected to the outside member with suitable webs in accordance with the practice of the art; 3 is the drive shaft of the pump; 4 and 5 are the pump runners suitably keyed or otherwise connected to the pump shaft; 6 is a bushing secured in the pump casing and acting as a bearing for the shaft 3; 7, 7, 7 are a plurality of cylinders

arranged around the bearing 6 as indicated in Fig. 2, and 8 is one of the plungers used in such cylinders for securing a feed of oil as hereinafter set forth.

The cylinders each communicate at their upper ends with a circumferential groove 9 and such circumferential groove communicates with the bearing surface 19 between the bushing 6 and the shaft by means of a plurality of perforations 10 arranged in suitable intervals around the circumference of the bushing. The piston 8 of each cylinder is normally pressed upward by means of a coil spring 11 placed between the top of the piston and the bottom of the cylinder. The cylinders are charged from an oil line 12 leading down from the surface of the ground and provided with a lateral passage 13 leading to the groove 9. A check valve in the form of a spring pressed ball 13^a serves to prevent any back flow through the passage 13. A suitable feed means (not shown) is provided at the surface of the ground for forcing oil down through the line 12 and charging the cylinder, the pressure being sufficient to force the plungers 8 down to the position illustrated, after which the springs function to feed the oil from the upper portions of the cylinders upward to the groove 9 and thence through the perforations 10 to the bearing surface between the bushing 6 and the shaft 3.

In order to support the oil line upon the pump casing the arrangement illustrated in Fig. 5 may be used, such construction showing the support of the oil pipe 12 and also of a pipe 12^a for indicating vacuum (the latter having nothing to do with the present invention) held in position by means of the screw 15. After the oil line passes the upper end of the pump casing it may be bent laterally if desired and carried up along the shaft casing 16 as shown in Fig. 3, which shaft casing is commonly employed in apparatus of this type, to support bearings for the shaft 3 intermediate the pump and the surface of the ground, such construction being one well known in the art. The supporting rings 17 may be employed and are clamped in position between the opposing ends of the shaft casing sections as illustrated. These rings can be adjusted circumferentially as desired so that the oil line may be kept straight from top to bottom

2
regardless of the rotary adjustment of the shaft casing sections. The oil line might be supported in a variety of ways other than the one illustrated, but this constitutes a simple and convenient method of supporting such line.

The foregoing provides for a reliable and continuous feed to the bearing, the arrangement being capable of multiplication to suit 10 requirements where there are a number of bearings. Each plunger feeds independently of the others so that a uniform feed at a plurality of discharge points is insured. The cylinders may be charged at intervals 15 or continuous pressure may be applied to the pipe line and in either case a substantially continuous feed is secured. The cylinders occupy a space in the inner pump casing which is otherwise not utilized, so that 20 the addition of the oil system requires no modification of the type of pump commonly used except in so far as the provision of the pockets for the reception of the cylinders is concerned.

23 Another feature of even greater importance is that for insuring that there will be no circulation of water along the bearing surface 19 between the bushing 6 and the shaft. In a pump of the kind shown 28 there is a pressure at the point 20 adjacent the upper end of the bearing and a suction at 21 at the lower end of the bearing tending to cause a downward circulation of 33 water along the bearing. This circulation carries along sand and dirt which, in the course of time, cut out the bearing causing friction losses and requiring a replacement of the bearing. To avoid this circulation the by-pass passages 22 are provided extending from the annular recess or chamber 23 at the top of the bearing to the space above the runner at the bottom of the bearing. These passages 22 being relatively 38 large and unrestricted at their end divert 43 any water and sand which enter the recess 23, so that such sand and water will not pass up along the surface 24 into the annular recess 25 and thence down along the bearing surface 19 between the bushing 6 48 and the shaft, but instead will pass directly down through the passage 22. The supply 53 of the oil through the perforations 10 also tends to prevent the injurious circulation along the bearing as heretofore referred to, 58 since there is a counter pressure of oil upward and downward from the perforations 10 tending to prevent any circulation of water. The supply of oil intermediate the 63 ends of the bearing therefore involves a decided advantage and in connection with the by-pass feature renders the bearing practically free from any requirement of replacement throughout the life of the pump. This feature of protecting the intermediate bearing of a pump may or may not be

used with the feature of the oil cylinders (although preferably so used) and it will be understood that the invention is not limited in this particular.

Fig. 6 illustrates a modification in which the cylinders 26 are located adjacent the outer wall 27 of the pump casing instead of being located closely adjacent the bearing 28. In this case a diagonal passage 29 provides for feed of oil from the top of the cylinder to 70 the groove 30 in the wall of the bushing, such groove in turn communicating with perforations 31 leading to the bearing surface of the bushing. A somewhat different type of plunger 32 is illustrated, such plunger 80 being forced up by the spring 33 in the same manner as in the other type of construction. Oil is fed to the cylinder through the passage 34 connecting to a suitable oil line supply pipe (not shown). In 85 this form of construction the casting 35 which carries the cylinders is separate from the main pump casting 36, the two castings being held together by means of suitable bolts 37. This arrangement provides 90 for convenient access to the cylinders. A passage 43 is provided here to permit pump pressure to be applied behind the plunger to counterbalance the pressure on the front of the plunger and to permit the escape of 95 liquid to the rear when oil is admitted to force the plunger to its starting position as illustrated. A similar expedient is employed in the other types shown, the cylinders all opening to the space above the 100 lower runner as indicated at 11^a (Fig. 1^a) in the bottom of the cylinder 7 of the Fig. 1 construction, thus facilitating the operation of the spring plunger and permitting the drainage downward of any sand or dirt 105 which may find entrance to the cylinders. The operation of the device is the same as that described in connection with the construction of Fig. 1.

Fig. 7 illustrates still another modification in which the drain passages 38 are placed in the bushing 39, instead of in the pump casting. These passages lead into the annular chambers 40 and 41 in which any sand entering has an opportunity to settle 115 and descend through the drain passages. Oil is supplied from the cylinders 42 as in the construction of Fig. 1.

What we claim is:

1. The combination with a pump casing, 120 an impeller or runner, and a drive shaft, of a bearing in the casing, a cylinder and plunger in the casing, a spring for causing relative movement between the plunger and its cylinder to expel the contents of the cylinder, a communication for supplying the oil expelled to the bearing, an oil line for conducting oil under pressure to the cylinder to compress the spring and charge the cylinder, and a check valve in the oil line 125

to prevent a back flow of oil therethrough.

2. The combination with a pump casing, an impeller or runner, and a drive shaft, of a bearing in the casing, a plurality of sets of cylinders and plungers in the casing, a spring for each cylinder and plunger for causing relative movement thereof to expel the contents of the cylinder, communications for supplying the oil expelled to the 10 bearings, an oil line, a communication therefrom to each cylinder, and check means for said communications to prevent a back flow of oil from the cylinders.

3. The combination with a pump casing, 15 a plurality of impellers or runners therein and a drive shaft for the impellers, of a bearing in the casing, a plurality of sets of cylinders and plungers in the casing, a spring for each cylinder and plunger for 20 causing relative movement thereof to expel the contents of the cylinder, communications for supplying the oil expelled from each cylinder to a bearing, a supply communication leading to each cylinder provided 25 with a check valve, and means for supplying oil under pressure to said last mentioned communications to charge the cylinders and compress the springs.

4. In combination in a pump, having an 30 impeller or runner and a drive shaft, an intermediate bearing for the shaft and the impeller, a by-pass paralleling the bearing and communicating with the same spaces at the top and bottom as those at the ends of 35 the bearing, and means for supplying lubricant under pressure to the bearing intermediate the ends thereof.

5. In combination in a pump having a 40 pair of spaced impellers or runners and a drive shaft, a bearing between the impellers, a by-pass to the side of the bearing extending through the pump casing from a point above one runner to a point below the other runner and communicating with 45 the spaces at the ends of the bearing, and means for supplying lubricant under pressure to the bearing intermediate the ends thereof.

6. In combination in a pump having a 50 pair of spaced impellers or runners and a drive shaft, a bearing for the shaft between the impellers, an annular chamber in the pump casing adjacent one end of the bearing, a by-pass extending from such 55 chamber to the space above the next impeller, and means for supplying lubricant under pressure to the bearing surface of the shaft intermediate the ends of the bearing.

7. In combination in a pump and power 60 transmission construction including, a drive shaft and impellers, of an externally threaded bearing for the shaft, a pair of shaft casing sections threaded upon the bearing with their ends in opposition but spaced 65 apart, and an oil pipe supporting fixture

provided with a flange adapted to be clamped between said opposing casing ends.

8. The combination with a pump casing, 70 an impeller or runner and a drive shaft, a bearing in the casing, a cylinder in the casing alongside the bearing, a plunger in the cylinder, a communication from one end of the cylinder to the bearing, a spring for pressing the plunger toward the outlet end of the cylinder to expel the contents thereof, an oil line for conducting oil under pressure to charge the cylinder and compress the spring, and a check valve in the oil line to prevent a back flow of oil therethrough.

9. The combination with a pump casing, 75 a plurality of runners or impellers and a drive shaft therefor, a series of bearings in the casing, a cylinder in the casing alongside each bearing, a plunger in each cylinder, a communication from one end of each cylinder to the adjacent bearing, a spring for pressing the plunger of each cylinder toward the outlet end thereof to expel the contents thereof, an oil line for conducting oil under pressure to charge the cylinders, a communication from the cylinders to the oil line, and a check valve for preventing a back flow of oil from the cylinders.

10. The combination with a pump casing 80 having a chamber, an impeller or runner, and a drive shaft, of a bearing in the casing, a cylinder and plunger in the casing, a spring for causing relative movement between the plunger and its cylinder to expel the contents of the cylinder, a communication for supplying the oil expelled to the bearing, an oil line for conducting oil under pressure to the cylinder to compress the spring and charge the cylinder, 100 and a check valve in the oil line to prevent a back flow of oil therethrough, a communication being provided between the cylinder to the rear of the plunger and said chambers.

11. The combination with a pump casing, 105 an impeller or runner, and a drive shaft, of a bearing in the casing, a cylinder and plunger in the casing with the axis thereof vertical, and with the cylinder opening downwardly to permit drainage, a spring for causing relative movement between the cylinder and plunger to expel the contents of the cylinder upwardly, a communication for supplying the oil expelled to the bearing and means for charging the cylinder above the plunger and compressing the spring.

12. The combination with a pump casing, 115 an impeller or runner, and a drive shaft, of a bearing in the casing, a cylinder and plunger in the casing, a spring for causing relative movement between the plunger and its cylinder to expel the contents of the cylinder, an outlet and communication from the cylinder whereby the oil expelled from

the cylinder is conducted to the bearing, and means for charging the cylinder with oil through said outlet.

13. The combination with a pump casing having a chamber, an impeller or runner in said chamber, and a drive shaft, of a bearing in the casing, an oil cylinder and plunger in the casing, a spring for causing relative movement between the plunger and its cylinder to expel the contents of the cylinder, a communication for supplying the oil expelled from the cylinder to the bearing, an oil line for conducting oil under pressure to the cylinder to compress the

spring and charge the cylinder, and a communication from the cylinder behind the plunger to the chamber.

14. A combination in a pump casing having a pair of spaced impellers or runners and a drive shaft, a bearing for the shaft between the impellers and a by-pass along one side of the bearing extending through the pump casing from a point above one runner to a point below the other runner and communicating with the spaces at the ends of the bearing.
